METHOD OF REPRODUCING FABRICS

Mack Leblang, Brooklyn, N. Y., assignor to
 Hazard Advertising Corporation, New York,
 N. Y., a corporation of New York

Application July 13, 1932, Serial No. 622,211

7 Claims. (Cl. 101—211)

This invention relates to the production of printed illustrations of merchandise for use in advertising folders, catalogues, and the like. More particularly, the invention is concerned with 5 a novel method of producing illustrations in color of knitted or woven goods, and particularly such goods as have an irregular surface which cannot be accurately reproduced in illustrations made by ordinary methods heretofore employed. The 10 new method offers special advantages in connection with the illustration of the colors in which silk stockings are made up, and an adaptation of the invention for that purpose will be described in detail for purposes of explanation, though it is 15 to be understood that the utility of the invention is not limited to the illustration of that particular material.

At the present time, it is the custom for manufacturers of stockings to supply their product in 20 many different colors, those colors now enjoying the widest popularity being light shades, for example, of brown. While the different shades are designated by names, the differences between the shades are so slight that the names have little 25 significance to the average purchaser. Accordingly, in sending out sales literature relative to their stockings, the manufacturers supply jobbers and other large purchasers with sample cards on which swatches of the goods are attached but 30 the cost of the material and of the labor in preparing the cards or folders prevents the wide distribution of the cards among consumers for advertising purposes. If a manufacturer could economically distribute folders containing printed 35 illustrations in color which show the different shades of the stockings and resemble the knitted material in appearance, his sales would undoubtedly increase, but heretofore no satisfactory process of producing such illustrations has been 40 available.

Attempts have been made heretofore to produce printed illustrations in color of stockings, for example, by the four color process, but when 45 that process is used, the resulting illustration is far from satisfactory because it contains no clean and sharp delineation of the individual threads or mesh of the goods, which is commonly referred to as the "gauge". In four color work, as is well known, the plates used print a multiplicity 50 of fine dots, the size and combination of which produces the different colors desired. In the case of stockings, however, it is not possible to obtain a sharply defined illustration of the gauge by means of plates produced by the four color 55 process, and while an illustration produced in this

manner may possibly give a correct representation of the color, the illustration does not have the appearance of a piece of stocking material, because the gauge is not visible.

Various other methods have also been tried in connection with the production of printed illustrations of stockings, but none of these methods produces satisfactory results, so far as I am aware, the principal deficiency being that the illustrations so made do not resemble stocking goods 5 in appearance. Also, these methods are expensive to use because the colors are produced by mixing of inks to achieve each individual shade and a folder which is to have several illustrations 10 in different colors must go through the press 15 once for each illustration.

In order to overcome these difficulties, I have devised a new method of producing illustrations of such materials as stockings, by which illustrations can be made which can be distinguished 20 from samples of the goods only upon close inspection. The new method is relatively simple to practice, involves substantially no more expense than the old four color process, and is 25 superior thereto in the results obtained.

For a better understanding of the invention, reference will be made to the accompanying drawing, in which

Fig. 1 is an enlarged face view of a portion of one printing plate used in practicing the new 30 process, this plate being used to print the gauge;

Fig. 2 is a sectional view through the plate shown in Fig. 1;

Figs. 3, 4, and 5 are enlarged face views of 35 portions of color plates used, and

Fig. 6 is a sectional view of one of the plates shown in Figs. 3, 4, and 5.

In practicing the new process in the production of colored illustrations of stockings, a number of printing plates are first prepared, one of 40 these plates being used to print the gauge lines and the others to apply the combinations of colors required to produce the actual color and shade of the goods. In many instances, a gauge plate and two color plates are enough, but in others, 45 it is necessary to employ three or four color plates to obtain the desired effect. These several plates may be advantageously made by photo-engraving processes, the actual preparation of individual plates being largely in accordance with 50 standard practice.

The gauge plate is made direct from the fabric and for this purpose a piece of the stocking is illuminated both from the front and rear and a line negative is made in the ordinary way. In 55

the exposure of the photographic medium, lighting of the stocking from front and rear is necessary to cause the gauge lines to be well defined and I have found that best results are obtained 5 when the illumination is arranged so that about three-quarters of the light comes from behind and through the stocking and one-quarter of the light illuminates its face. After making the line negative, a contact positive is made therefrom and 10 the various other well-known operations including etching are carried on to produce a printing plate from the positive, the plate having lines on its printing face corresponding to the lines of the gauge in reverse. The printing face of this plate is illustrated in Fig. 1 in which the raised portions 15 of the plate carry the printing ink.

For some colors, it is sufficient to produce a line negative of the gauge and a contact positive therefrom, with the printing plate produced from the 20 positive in the manner described. For other colors, tinting must be employed to obtain the correct final color. For this purpose, a line negative and a contact positive are made in the usual way. A negative is then made of a plain white surface 25 through a screen. This negative is then placed against the face of the contact positive and a metal plate having a sensitized surface is exposed to the positive and the negative made through the screen. The printing areas on the plate are 30 thus filled with dots instead of being solid. The intensity of the exposure through the screen will depend on the color of the material to be reproduced and the making of the negative from the screen will be in accordance with standard practice known to any person skilled in the art.

The other printing plates used for making the 35 illustrations are for color purposes and the production of each plate involves photographing a plain white surface through a screen having rows 40 of dots. The intensity of the exposure through the screen in each case will depend on the desired final color effect and the particular color which is to be printed from the plate made from the screen.

45 Each color plate so made, as for example, that illustrated in Fig. 6, has dots 11 thereon in rows, the tops of the dots carrying the ink. The plates 12, 13, and 14 to be used in making the same illustration have their rows of dots at different angles, 50 as shown, and this is accomplished by tilting the screens to different positions when the negatives are made. When the gauge plate is tinted, the screen is applied in a different position from those used in making the color plates.

55 Upon completion of the plates, proofs are made therefrom in the usual way, the color plates being preferably printed first and the gauge plate last. If the plates are not found satisfactory for the production of the desired color, corrections are 60 made, as for example the plates may be altered by hand by cutting down the size of the dots or by burnishing the plates to spread the dots. If necessary, one or more new color plates may be made, although ordinarily a skilled workman will 65 be able to make plates to produce the desired color without difficulty.

70 Upon completion of the plates, a transfer is made from the gauge plate and from this is made an embossing die. This is to be used for embossing the printed illustration and it is so prepared that the embossed illustration gives the same effect as the actual stocking.

75 In producing an illustration, the plates are inked with the proper colors and the surface on which the illustration is to appear receives an

impression from each plate, the gauge plate being printed last. The printing plates having the dots are preferably inked with inks of the primary colors, and the line or gauge plate will be inked with brown for nearly all shades of stockings, the shade of brown varying with the shade of the stocking material. Even though the ink employed on the line or gauge plate is of the same shade, or is closely similar to that of the stocking, the lines will be visible because the dot plates 10 merely produce a background of a single shade, whereas the line or gauge plate prints lines on that background. However, if desired, the color of the ink used on the line or gauge plate may be a shade slightly darker than that of the background. The illustration is then embossed by an embossing die having recesses corresponding to the lines of the line or gauge plate to impart to the illustration the same color effect as the stocking, the gauge lines are visible as in the 20 goods, and the gauge lines stand out because of the embossing. As a result of these several factors, the illustration closely resembles an actual sample of the goods and the difference can be detected only upon close inspection.

25 With my process, and using inks of the same four colors, it is possible to obtain many distinct shades in the illustrations by varying the sizes of the dots on the plates. Three or four plates must be made for each illustration, but similar 30 plates for all illustrations may be printed at the same time and from the same ink, so that a card having illustrations representing many different stockings may be printed simultaneously from the same inks.

What I claim:

1. A method of making printed illustrations in color of materials, which comprises preparing a line negative of the material illuminated partly from the front and partly from the rear, preparing a positive from said negative, making a printing plate from said positive, said plate being adapted to produce a representation in color of the lines of the material appearing in said negative, preparing color printing plates provided with 45 printing dots arranged in rows, the angles of the rows differing in the different plates, subjecting the surface which is to carry the illustration to impressions from said color plates successively, each plate being inked a different color, printing on said surface from said first plate, and deforming said surface to make it conform to the character of the surface of said material.

2. A method of making printed illustrations in color of materials, which comprises preparing a 55 line negative of the material illuminated partly from the front and partly from the rear, preparing a positive from said negative, making a printing plate from said positive, said plate being adapted to produce a representation in one color 60 of the lines of the material appearing in said negative, preparing color printing plates provided with printing dots arranged in rows, the angles of the rows differing in the different plates, preparing an embossing die from said first plate, said die having recesses corresponding to said lines, subjecting the surface which is to carry the illustration to impressions from said color-printing plates being inked different colors, subjecting said surface 65 to impressions from the line plate, and embossing said printed surface.

3. A method of making printed colored illustrations of a fabric, which comprises preparing a line negative of the fabric illuminated partly 75

from the front and partly from the rear, preparing a positive from said negative, exposing a sensitized metal surface to said positive through a screen, treating said plate to prepare it for use in printing, preparing color printing plates provided with printing dots arranged in rows at different angles, subjecting the surface which is to carry the illustration to impressions from said color plates successively, each plate being inked a different color, printing on said surface from said first plate, and embossing said printed surface to give it surface irregularities corresponding to those of said fabric.

4. The method of making printed illustrations of fabrics such as stocking material in the color of the material, which comprises illuminating the texture of the material partly from the front and partly from the rear, photographically reproducing the texture of the material while it is so illuminated to form a negative showing the gauge lines of the material, preparing a positive printing plate from said negative, preparing color printing plates provided with printing dots arranged in rows, the angles of the rows differing in the different plates, subjecting the surface which is to carry the illustration to impressions from said color-printing plates successively, said color-printing plates being inked different colors, subjecting said surface to impressions from the line plate.

5. The method of making printed illustrations of fabrics such as stocking material in the color of the material, which comprises illuminating the texture of the material partly from the front and partly from the rear, photographically reproducing the texture of the material while it is so illuminated to form a negative showing the gauge lines of the material, preparing a positive printing plate from said negative, preparing color printing plates provided with printing dots arranged in rows, the angles of the rows differing in the different plates, subjecting the surface which is to carry the illustration to impressions

from said color-printing plates successively, said color-printing plates being inked different colors, subjecting said surface to impressions from the line plate, and deforming said surface to give it surface irregularities to conform to those of the material.

6. The method of making printed illustrations of fabrics such as stocking material in the color of the material, which comprises illuminating the texture of the material partly from the front and partly from the rear, photographically reproducing the texture of the material while it is so illuminated to form a negative showing the gauge lines of the material, preparing a positive printing plate from said negative, preparing color printing plates provided with printing dots arranged in rows, the angles of the rows differing in the different plates, subjecting the surface which is to carry the illustration to impressions from said color-printing plates successively, said color-printing plates being inked different colors, subjecting said surface to impressions from the line plate, and embossing said surface to make it conform to that of said material.

7. The method of making printed illustrations of fabrics such as stocking material in the color of the material, which comprises illuminating the texture of the material partly from the front and partly from the rear, photographically reproducing the texture of the material while it is so illuminated to form a negative showing the gauge lines of the material, preparing a positive printing plate from said negative, preparing color printing plates provided with dots arranged in rows, the angles of the rows differing in the different plates, subjecting the surface which is to carry the illustration to impressions from said color-printing plates successively, said color-printing plates being inked different colors, and thereafter subjecting said surface to impressions from the line plate.
